UNITED STATES PATENT OFFICE.

CHARLES WARREN, OF ROCKFORD, ILLINOIS.

PUMPER-PEDAL ACTION FOR INTERIOR PLAYER-PIANOS.

963,262.

Specification of Letters Patent.

Patented July 5, 1910.

Application filed August 20, 1909. Serial No. 513,755.

To all whom it may concern:

Be it known that I, CHARLES WARREN, a citizen of the United States, residing at Rockford, in the county of Winnebago and State of Illinois, have invented new and useful Improvements in Pumper-Pedal Action for Interior Player-Pianos, of which the following is a specification, reference being had to the accompanying drawings, 10 forming a part thereof.

The purpose of this invention is to provide an improved construction for the mounting and action of the pumper pedals of an interior player piano, which are drawn 15 forward for use and thrust back out of protruding position when the piano is to be operated manually.

It consists in the elements and features of construction shown and described as indicated in the claims.

In the drawings:—Figure 1 is a vertical fore-and-aft section through a portion of an upright piano case provided for this invention, showing the parts of the invention 25 in side elevation. Fig. 2 is a plan view of the pumbers and their supports. Fig. 3 is a partly sectional detail front elevation of the pumper connections, section being made at the line 3—3, on Fig. 2. Fig. 4 is a fore 30 and aft section at the line 4—4, on Fig. 2.

The pumbers, A, A, are mounted under the foundation board, B, of the upright piano shown in the drawing, the moving member, A¹, of the pumper bellows being 35 the upper member, said upper members being each connected by a thrust rod, C, with an operating lever, D, having a fixed fulcrum on a bracket, D¹, mounted on the bottom board, E, of the case. The lever, D, 40 has its forward arm jointed at d² for folding upward the forward member, D², as seen in dotted line in Fig. 1, when the pedals are not in use. Said forward member carries at its forward end a roll, D³, which 45 bears on the underside of the pedal, M. The pedals, M, M, are fulcrumed at their forward ends on the longitudinal bar, F, from whose ends fore-and-aft arms, F¹, F², extend to sliding carriages, G, G, which are 50 connected together by a longitudinal rod, G¹, and mounted for sliding on two fore-and-aft fixed slide rods or tracks, H, H, which are strongly supported in hangers, h, h, projecting downward from the bottom 55 of the frame structure of the case.

The construction thus far described, it will be observed, permits the pedals, M, to be first lifted for folding back the forward members, D², of their operating levers, and then to be let down so as to lie in the plane 60 of the fore-and-aft arms, F¹, of the pedal-carrying device, and then to be moved rearward edgewise with that pedal-carrying device to a position under the bottom board, E. In the absence of means to prevent such 65 a result, this construction involves the liability of pushing the pedals rearward or inward when operating the same, necessitating frequent readjustment of their position at considerable inconvenience to the operator. 70 To prevent this inconvenience, there is provided upon the lower side of the bottom board, E, a latch, N, pivoted at its rear end to said bottom board, E, and of such length that its forward end will drop in behind the 75 longitudinal rod, G¹, which connects the carriages, G, G, when said carriages are at their forward position holding the pedals protruded in operative position, the latch being adapted to clear the rod, G¹, when lifted 80 up against the under side of the board, E. On the upper side of said bottom board, E, there is mounted a pneumatic, K, whose upper wall is the moving wall and is connected by a link or finger, K¹, with the latch, N, 85 extending down through the bottom board, E, for connection with said latch. The latch, N, may be a spring bar obtaining substantially pivotal connection by its flexibility at a point just forward of its fastening to the 90 board, E, or there may be a spring, L, operating on the latch to uphold it. Such spring, L, may be, as shown in Fig. 3, contained within the pneumatic, K, operating 95 directly on the moving wall of the pneumatic and through the link or finger, K¹, upon the latch to lift the latter by expanding the pneumatic. When the spring operates upon the moving wall of the pneumatic, obviously the element, K¹, must be connected 100 to the latch, not merely arranged to press upon it. When the latch is itself a spring, as illustrated and described, any other spring may be dispensed with, and the positive connection of the lower end of the element, K¹, 105 to the latch is not necessary. In the construction shown, both a spring latch and a spring in the pneumatic are shown, both co-operating to the same result. The pneumatic, K, is in communication by means of 110

- a narrow duct, P, with any exhaust chamber with which the pumbers are connected for maintaining exhaust air supply for the well understood purposes of a pneumatic action.
- 5 Such exhaust chamber is represented at R, and it will be understood that in any familiar manner the pumbers are connected with such chamber, and the connection is not specifically illustrated. When the pumbers are 10 drawn forward at a position of use, as shown in Fig. 1, the first action upon them operating the pumbers producing an exhaust tension in the air chambers causes the pneumatic, K, to be collapsed and the latch, N, 15 to be dropped in front of the rod, G¹, where it will be held so long as there is any exhaust tension maintained by the pumbers operative for playing. That is to say, the spring, wherever positioned for upholding the latch, 20 will be adequate only to support the weight of the latch and the upper member of the pneumatic, K, and will yield upon very slight rarification of the air in the pneumatic. As soon as the operator ceases to 25 use the pedal and the air in the chamber resumes normal atmospheric tension, the expansion of the pneumatic, K, will cause or permit the latch to be lifted out of the way of the rod, G, so that the pedals may be 30 dropped and thrust under the bottom board, E, requiring no thought or action of the operator for releasing the latch, the proper conditions resulting merely from the cessation of playing.
- 35 I claim:—
1. In an interior player piano, in combination with the case, exhaust devices mounted in the case; pumper pedals for operating such exhaust devices; a carrier for the 40 pumper pedals adapted to be retracted for withdrawing the pedals from operative position; a latch for locking the carrier at operative position of the pedals, and a pneumatic connected with a chamber influenced

by the pumbers and operatively connected 4 with the latch.

2. In an interior player piano, in combination with the case, exhaust devices mounted therein comprising pumbers; a pair of fore-and-aft parallel slide bars mounted on the 5 bottom of the case; carriages sliding on said bars and a longitudinal rod rigidly connected with the carriages; parallel links pivotally connected to the carriages and extending forward therefrom and provided with a 5 connecting bar at their forward ends; pedals fulcrumed on said connecting bar; a latch mounted on the case positioned for engagement behind said longitudinal bar when the carriages are at forward position; a pneumatic operatively connected with said latch and having communication with a chamber influenced by the pumbers.

3. In a pneumatically operated musical instrument, pumbers and pedals for operating the same, a carrier for the pedals adapted to be retracted for withdrawing the pedals from operative position; a device for locking the carrier at operative position of the 6 pedals, and means by which the pumping 7 action of the pedals operatively positions the locking device.

4. In a pneumatically-operated musical instrument, pumbers and pedals for operating the same; a carrier for the pedals adapted to be retracted for withdrawing the pedals from operative position; a device for locking the carrier at operative position of the 7 pedals, and a pneumatic for operating said locking device.

In testimony whereof, I have hereunto set my hand, in the presence of two witnesses, at Chicago, Illinois, this 7th day of August, 1909.

CHARLES WARREN.

In the presence of—

JULIA S. ABBOTT,
CHAS. C. BURTON.
